UNITED STATES PATENT OFFICE.

CARL CULMAN, OF HUNTINGTON PARK, CALIFORNIA.

PIVOT POLISHER.

Application filed January 19, 1920. Serial No. 352,600.

To all whom it may concern:

Be it known that I, CARL CULMAN, a citizen of the United States, and residing in the city of Huntington Park, California, 5 have invented the new and useful Improvement in Pivot Polishers, of which the following is a specification.

This invention relates to abrading devices adapted particularly to polish pivots of 10 watches, etc.

The operations on parts of watches and the like are delicate operations; accordingly, the conditions encountered are different entirely from those encountered in mechanical 15 operations generally and accordingly, require delicate mechanisms. This is especially true since the abrading operations are usually on pivot parts in which the material removed must not only be small, 20 but the pressure on the part operated upon must be very light.

One of the objects of this invention, therefore, is to provide an abrading device which is capable of performing the delicate 25 operations on the delicate parts of mechanisms.

Another object is to provide an abrading device which is simple in construction, effective in its operation, and can be used 30 on an ordinary jeweler's lathe, and with an ordinary balance chuck.

Further objects will appear from the detail description taken in connection with the accompanying drawing, in which:

35 Figure 1 is a side elevation showing a part of the jeweler's lathe, a balance chuck and illustrating the abrading element embodying this invention;

Figures 2 and 3 are sections on the line 40 2-2, Figure 1, illustrating the operations; and

Figures 4 to 7 inclusive are diagrammatic views illustrating the operation.

Referring to the accompanying drawing, 45 and more particularly to Figures 1 to 3 inclusive, 1 designates a bed of an ordinary jeweler's lathe having a head stock 2, a tail stock 3 provided with the usual clamping device 4 and with any suitable adjusting device 5 for throwing the spindle 6 laterally off center. The live spindle 7 is provided with a balance chuck 8, such as shown in United States Patent No. 760,314, granted May 17, 1904. This balance chuck is provided 55 with a removable cap 9 providing a side face 10 and having also a central

aperture through which projects the balance pivot 11 of a balance arranged within the hollow chuck. The pivot 11 is shown considerably enlarged for the sake of clearness, 60 but in practice, it will be very small.

Arranged to be forced on and retained on the spindle 6 is a collar 12 which carries a head 13 provided with spaced arms or lugs 14 bored to receive a shaft 15. This 65 shaft has mounted thereon a driving element 16 provided with a friction facing 17 of cork or the like adapted to bear against the side face 10 of the chuck. This driving element is arranged to have a 70 frictional connection with the shaft 15 by forcing the shaft into a yielding bushing 18 on the driving element. Mounted also on the shaft is an abrading element comprising a grinding part 19 and a polishing 75 part 20, either one of which is arranged to engage the work 11 as shown respectively in Figures 2 and 3. This abrading element also has a yielding sleeve or bushing 21 so as to provide a frictional connection between 80 the shaft and the element.

When the shaft 15 is set radially so that the center thereof will intersect the center or rotation of the chuck 8 as shown in Figure 2, and if the driving element is now moved 85 against the face 10 so that the shaft 15 will be revolved as the chuck revolves carrying the abrading element with it, the forces are such that the abrading element will have a radially outward pull exerted thereon, no 90 matter in which direction the chuck rotates.

This will be clear from a consideration of the diagrams, Figures 4 and 5. Assuming that the direction of rotation of the chuck is as indicated by the direction of the arrows, Figures 4 and 5, thereby causing rotation of the abrading element in the direction of the arrow; the friction surface 17 will be slightly flattened at the point of contact as shown in Figure 4 and the pressure between the leading portions *a* of the point of contact and the center *c* will be greater than the pressure between the lagging side *b* and the center *c*. Now in view of the fact that every particle when traveling from *a* to *b* 100 will travel on the arc of a circle *d*, Figure 5, which arcs lie in the face 10 of the chuck 8, there are two forces acting on this particle as it travels from *a* to *b*, namely a force *e-f* tending to move the particle outwardly 105 radially and a force *f-g* tending to move the particle inwardly radially. In view of

the fact, however, that, as explained above, the pressure between *a* and *c* is greater than between *b* and *c*, *e*—*f* is greater than *f*—*g*; accordingly, the radial resultant *h*—*f* of the force *e*—*f* is greater than the radial resultant *f*—*i* of the force *f*—*g*; accordingly, there is a net resultant force *h*—*i* tending to move each particle of the surface 17, in contact with the surface 10 of the chuck 10 outwardly. This is true no matter what the direction of rotation of the chuck may be. Accordingly, it is true where the direction of rotation of the chuck is as shown in Figure 2.

15 This feature causes a radial outward movement of the shaft 15 as it is rotated thereby tending to carry the abrading element with it; accordingly, the abrading head is retained yieldingly against the work 20 11 so that the work will be abraded.

In many classes of work, it is necessary to provide for two operations, namely a grinding operation and a polishing operation, and it is for this purpose that the abrading element is provided with a grinding part 19 and the polishing part 20. The grinding and polishing parts can be interchangeably rendered effective by reversing the abrading element; this however, takes time and 30 may also interfere with the delicate operations on the delicate parts operated upon. In accordance with this invention, therefore, means are provided for selectively retaining either end of the abrading element 35 in engagement with the work without requiring detachment of that element.

Referring to Figure 3, the abrading element has been moved outwardly radially on the shaft 15 so that its polishing part 20 40 will now engage the work. In order, however, to retain the polishing head in engagement with the work, the force applied to the shaft 15 must be reversed so that there will now be exerted an inward radial pressure on the shaft and on the abrading element. This is accomplished as follows:

Referring first to Figure 6, assume that the medial contact point *c* is shifted to one side of the center, which can be accomplished 50 by shifting the spindle 6 by manipulation of an adjusting device, such as 5; it will be noted that if the direction of rotation is as indicated in Figure 6, the resultant *f*—*i* is in the same direction as *h*—*f* and accordingly, the radial force *h*—*i* is the sum of the resultant forces instead of a difference of 55 the same as in Figure 5, when the line of contact passes through the center of rotation of the chuck; accordingly, when the chuck 60 is rotated in the direction of the arrow 7, the resultant force on the connected driving and abrading elements will be a radial outward force.

Assume now that the direction of rotation 65 is as shown in Figure 3, then it will be clear

from Figure 7 that the resultant force *i*—*h* will now be a radial inward force. Accordingly, the pressure applied to the abrading head is such as to cause the polishing part 20 to press against the work. 70

In practice the direction of rotation of the polishing head is as indicated in Figures 2 and 3. When grinding as the first operation, the spindle 6 is set on center thereby causing the grinding part 19 to be 75 pressed yieldingly against the work to grind the same. In order now to polish the work, the center is moved to the right, Figure 1, carrying the abrading device with it, the spindle 6 is moved off-center, as shown in 80 Figure 3, the abrading element is moved up on the shaft 15 and the spindle 6 is moved to the left again, thereby causing the polishing part to now yieldingly engage the work to polish the same. The same results may, 85 however, be accomplished by initially setting the spindle 6 off center, when the operations may be readily obtained by the simple reversal of the rotation of the chuck. 90

In Figures 2 and 3, the shaft 15 is arranged angularly on opposite sides of center; this is, however, not necessary since the direction of pressure is reversed irrespective of any angular position of the shaft 15, since 95 that is determined by the eccentricity.

It will, therefore, be seen that the invention accomplishes its objects. The device has such a structure as to enable the delicate operations on the delicate parts requiring treatment. The frictional connection of the driving and abrading elements provides for a yielding pressure as well as a yielding abrading action. The device is exceedingly simple in construction, cheap to manufacture, and can be applied to the ordinary jeweler's lathe and, therefore, requires no added expense. 100

It is obvious that various changes may be made in the details of construction without departing from the spirit of this invention; 110 it is, therefore, to be understood that this invention is not to be limited to the specific details shown and described.

I claim—

1. A device of the class described, comprising, a rotary work holder, and an abrading device having a part engaging the work and having a part engaging and driven by said holder, adapted by the action of the driving force transmitted by said holder to said holder engaging part, to retain said work engaging part in engagement with the work. 115

2. A device of the class described, comprising, a rotary work holder, an abrading element, a driven element connected with said abrading element and engaging the side face of said holder, adapted upon such engagement and by the action of the driving force transmitted by said holder, to retain 125 130

said abrading element in engagement with the work.

3. A device of the class described, comprising, a rotary work holder, and connected abrading and driven elements arranged radially of said holder with said driven element engaging the side face of said holder eccentrically thereof, whereby said driven element is adapted upon such engagement

10 to retain said abrading element in engagement with the work.

4. A device of the class described, comprising, a rotary work holder, and connected abrading and driving elements arranged radially of said holder with said driving element engaging the side face of said holder eccentrically thereof, whereby said driving element is adapted upon such engagement and upon selective shifting of said driving

15 element to selectively retain either face of

said abrading element in engagement with the work.

5. A device of the class described, comprising, a rotary face plate having a radial driving face, an abrading wheel, a driven wheel mounted with its axis substantially radially of said plate with its periphery engaging the driving face thereof, and a driving connection between said wheels.

6. A device of the class described, comprising, a rotary face plate having a radial driving face, an abrading wheel, a driven wheel mounted with its axis eccentric but substantially radially of said plate and with its periphery engaging the driving face thereof, and a driving connection between said wheels.

In testimony whereof I affix my signature this 17th day of Sept., 1919.

CARL CULMAN.
